CLAIM

The ornamental design for a surface pattern applied to a doughnut pastry, as shown and described.

DESCRIPTION

FIG. 1 is a top side perspective view of a surface pattern applied to a doughnut pastry showing our new design;

FIG. 2 is a top plan view thereof;

FIG. 3 is a front elevational view thereof;

FIG. 4 is a right side elevational view thereof;

FIG. 5 is a left side elevational view of the environmental doughnut pastry; and,

FIG. 6 is a bottom plan view of the environmental doughnut pastry.

The doughnut pastry is shown in broken lines for illustrative purposes only and forms no part of the claimed design.
